UNITED STATES PATENT OFFICE

2,638,060

DISCHARGE OUTLET FOR RAILWAY CARS

George B. Dorey, Westmont, Quebec, Canada, assignor to Enterprise Railway Equipment Company, Chicago, Ill., a corporation of Illinois

Application June 29, 1949, Serial No. 102,105

7 Claims. (Cl. 105—282)

1

This invention relates, generally, to railway cars of the hopper type, and it has particular relation to the discharge outlets therefor in which the outlet is formed by a four sided frame with a sliding gate for controlling the size of the discharge opening.

Among the objects of this invention are: To support and guide the gate throughout its full range of movement between open and closed positions; to prevent upward movement of the gate without providing stops therefor above its surface; to fashion the frame so that the runways or guides for the gate can be machined without interference by a side wall of the frame; to fashion the frame with the portion of the side wall above the slot through which the gate moves omitted and later supplying this wall portion as a separate item and securing it in position after the runways or guides have been machined; and to construct the frame with a view to casting it without using large molds or complex cores.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following detailed description, taken together with the accompanying drawings, in which:

Figure 1 is a top plan view of a discharge outlet for railway cars constructed in accordance with this invention, certain parts being broken away in order to show certain construction features;

Figure 2 is a view, in end elevation, looking in the direction of the arrows along line 2—2 of Figure 1;

Figure 3 is a view, in side elevation, of the discharge outlet shown in Figure 1;

Figure 4 is a detail sectional view, at an enlarged scale, taken along the line 4—4 of Figure 1;

Figure 5 is a detail sectional view of the discharge outlet showing the gate in the open position;

Figure 6 is a detail sectional view, at an enlarged scale, taken along the line 6—6 of Figure 1; and

Figure 7 is a plan view of the bottom of the gate which is employed for closing the opening through the discharge outlet.

2

Referring now particularly to Figures 1, 2 and 3 of the drawings, it will be observed that the reference character 10 designates, generally, a rectangular cast iron frame which has an upper vertical side wall 11 and outflared or inclined upper end and side walls 12 and 13. The walls 11, 12 and 13 extend over a suitably shaped car hopper 14 which is indicated by broken lines in Figure 3. The walls 11, 12 and 13 are cast integrally with the frame 10 along three of its sides. The wall along the fourth side opposite the end wall 12 is not formed integrally with the other walls and with the frame 10 in order to facilitate machinery of certain runway or guide surfaces which will be described presently.

As illustrated in Figures 3 and 5, the frame 10 also comprises a vertical lower side wall 17, vertical lower end and side walls 18 and 19, and an inclined lower end wall 20. It will be understood that these walls 17, 18, 19, and 20 are cast integrally with the frame 10. The lower side walls 17 and 19 have angular rearwardly extending portions 21 and 23 which are provided with upper flanges 25 and 27, respectively, to form a generally T-shape as shown more clearly in Figure 4. The upper surfaces of the flanges 25 and 27 are machined to provide runway or guide surfaces 29 on which a generally rectangular cast iron gate, shown generally at 30 in Figure 7, is arranged to slide. The gate 30 has under surfaces 31 along its edges which are machined so as to slide readily along the runway or guide surfaces 29 on the upper sides of the upper flanges 25 and 27 as will be understood readily. These machined surfaces 29 and 31 also serve by their intimate and complete contact to seal the sides of the discharge outlet so as to prevent the flow of finely divided lading therewith.

As shown in Figure 5, the upper surface 32 of the vertical lower end wall 18 is machined for interfitting with an under surface 33, Figure 7, along the forward edge of the gate 30 when it is in the closed position. This construction also prevents the discharge of lading along the forward edge of the gate 30 when it is closed.

An important feature of the present invention is the means for holding the gate 30 in the closed position in the frame 10. For this purpose guide plates 34, Figure 7, are provided along the under surface of the gate 30 at its sides. They are spaced from the gate 30 by bosses 35, Figure 4, and flanges 36 which are cast integrally with the gate 30. Rivets 37, or other suitable holding means, extend through the bosses 35 and the guide plates 34 to hold the latter in position along the under side of the gate 30. Integrally formed

with the plates 34 are extensions 38 which, as shown more clearly in Figure 4, underlie the upper flanges 25 and 27 of the side walls 11 and 13. The extensions 38 are spaced slightly from the undersides of the flanges 25 and 27 so as to permit the gate 30 to be moved freely into and out of the closed position. The under surfaces 31 along the sides of the gate 30 and the upper surfaces of the extensions 38 together define U-shaped slots 39 that cooperate with the flanges 25 and 27 which project into them.

As illustrated in Figure 5, the inclined lower end wall 20 has a horizontal portion 40 along its upper edge which is depressed at its ends as indicated at 41, Figure 4, to accommodate the guide plates 34. The upper surface of this horizontal portion 40 defines the lower edge of a narrow rectangular opening 42 through which the gate 30 is slideable to and from the closed position as shown in Figure 5. The upper side of this rectangular opening 42 is defined by the lower edge 43 of one leg 44 of an angle 45 which forms the rear upper side wall for the frame 10. The angle 45 includes another leg 46 which extends at right angles to the leg 44.

Another important feature of this invention is the fashioning of the frame 10 so as to receive the angle 45. Since the space between the upper side walls 11 and 13 is open, it is possible to machine the runway or guide surfaces 29 along the upper sides of the flanges 25 and 27 without having to take into account a transversely extending wall such as would be the case if the rear wall which is formed by the angle 45 were cast integrally with the frame 10. It will be understood that the angle 45 may be welded in place. As shown in Figure 1 it may be welded as indicated at 47 to the vertical upper side wall 11. Provision can be made for welding its other end as indicated at 48 to the side wall 13.

With a view to sealing the juncture between the gate 30 and the leg 44 of the angle 45, a rib 49, Figure 6, is cast integrally with the gate 30 and, as here shown, it is arranged to abut the rear side of the lower portion of the leg 44. In this manner and the manner described hereinbefore a tight seal is provided around the edges of the gate 30 in the frame 10 when the former is in the closed position.

Any suitable means can be provided for moving the gate 30 to and from the closed position. As shown in Figure 7 a rack, indicated generally at 52, may be provided. The rack 52 comprises teeth 53 which may be cast integrally with the gate 30. Alternate teeth 54 extend substantially to the edges of the gate 30 in order to reinforce the same. As shown in Figure 6 a pinion 55 cooperates with the teeth 53 of the rack 52. The pinion 55 may be fast on a shaft 56 which extends transversely of the frame 10 and through the angular rearwardly extending portions 21 and 23 of the side walls 11 and 13. Any suitable means, not shown, may be provided for rotating the shaft 56 as will be understood.

It is desirable to lock the gate 30 in the closed position. For this purpose bulbous sections 57 are formed integrally therewith along its rear edge as illustrated in Figures 6 and 7 of the drawings. A swinging locking cam, shown generally at 58, Figure 1, which interfits with the bulbous sections 57 and are rockably mounted thereon by a shaft 60. The cam 58 has a curved outer surface 61 which, in the locking position, bears against stops 62 which may be cast integrally with the portions 21 and 23 of the frame

10. The end portions 63 of the cam 58 are shorter than the central portion 64 so as to permit the latter to project downwardly between the flanges 25 and 27 as shown more clearly in Figures 3 and 6 of the drawings.

In order to unlock the gate 30 the cam 58 is swung in a clockwise direction as viewed in Figure 3 out of engagement with the stops 62. Thereafter the shaft 56 can be rotated to rotate the pinion 55 and withdraw the gate 30 from the opening defined by the walls of the frame 10. When the gate 30 is closed, the end portions 63 of the cam 58 ride up the inclined surfaces 65, Figure 3, of the stops 62. When the gate 30 has been moved to the fully closed position, the cam 58 drops by gravity into the locked position against the stops 62.

Chute receiving members 67, 68, 69 and 70 may be secured by rivets 71 to the walls 11, 12, 13 and 20 respectively. The member 67 is generally hook-shaped while the members 68 and 69 are in the form of angles. The member 70 also is of hook-shape. The provision of these chute receiving members forms no part of the present invention.

It will be understood that the car hopper 14 has four sides forming a discharge opening and that the upper side and end walls 11, 12 and 13, which are cast integrally with the frame 10, are arranged to interfit with three of the four sides of the hopper 14. The leg 44 of the angle 45 interfits with the fourth wall of the hopper. The lower side and end walls 11, 12, 13, and 20 define a four sided chute the opening through which is closed off by the gate 30. The sides of the gate 30 are guided by vertical side wall portions 11a and 13a which, as shown in Figures 2 and 4, constitute the lower portions of the upper side walls 11 and 13 respectively.

40 An additional seal for the rear edge of the gate 30 is provided between the lower edge of the leg 46 of the angle 45 and the juxtaposed portions of the bulbous sections 57 of the gate 30 and the coextensive arcuate surfaces of the arms 59. It will be noted that these surfaces are concentric arcuate shaped surfaces on a common radius extending from the shaft 60 and that they engage the lower edge of the leg 46 along its entire length when the gate 30 is closed, thereby closing off the space therebelow.

55 Preferably the shaft 56 is journaled in bearing pads 72, Figures 3 and 4, which are cast integrally with the frame 10 outside of the extensions 21 and 23 of the side walls 11 and 13 and between the vertical planes containing the outer sides of the vertical side wall portions 11a and 13a.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

65 What is claimed as new is:

1. In a discharge outlet for railway cars or the like having a discharge opening, in combination, a rectangular frame defining an opening registering with said discharge opening and including 70 upstanding upper side walls and depending lower side walls spaced inwardly therefrom having horizontally disposed portions uniting the respective upper and lower side walls and forming runways extending inwardly beyond said lower side walls, 75 a gate slideable on said runways for closing said

opening in said frame, and a flange underneath each side of said gate extending underneath the respective runway to retain said gate on said runways.

2. In a discharge outlet for railway cars or the like having a discharge opening, in combination, a rectangular frame defining an opening registering with said discharge opening and including upstanding upper side walls and depending lower side walls spaced inwardly therefrom having horizontally disposed portions uniting the respective upper and lower side walls and forming runways extending beyond said side walls, a gate slideable on said runways for closing said opening in said frame, and guide means carried by and extending laterally from the underside of said gate underneath said horizontally disposed portions and cooperating therewith to retain said gate in position.

3. In a discharge outlet for railway cars or the like having a discharge opening, in combination, a rectangular frame defining an opening registering with said discharge opening and including sides of angular cross-section each having a horizontally disposed portion forming a runway with an integral upwardly extending upper side wall spaced outwardly therefrom and a depending integral lower side wall intermediate its edges, a gate slideable on said runways for closing said opening in said frame, and a flange underneath each side of said gate extending underneath the respective runway to retain said gate on said runways.

4. In a discharge outlet for railway cars or the like having a discharge opening, in combination, a rectangular frame defining an opening registering with said discharge opening and including sides of angular cross-section each having a horizontally disposed portion forming a runway with an integral upwardly extending upper side wall spaced outwardly therefrom and a depending integral lower side wall intermediate its edges, a gate slideable on said runways for closing said opening in said frame, and guide means carried by and extending laterally from the underside of said gate underneath said horizontally disposed portions and cooperating therewith to retain said gate in position.

5. In an outlet assembly for a load containing hopper having a discharge opening and a gate for closing it, in combination, a rectangular frame defining an opening registering with said discharge opening and having runways extending laterally for slidably supporting said gate, means for guiding said gate in its movement including upwardly extending side walls spaced outwardly from said runways, and means for moving said gate including a rack on its underside and a cooperating pinion on a shaft, and bearings for said

shaft comprising pads below said runways and carried by said side walls, the outer surfaces of said pads being disposed within the planes of the outer surfaces of said side walls.

5. 6. In an outlet assembly for the discharge opening of a load containing hopper, in combination, a four sided frame having an open registering with said discharge opening and a sliding gate for closing said opening, one end of said frame being slotted for the passage of said gate therethrough, runways at the sides of said frame and projecting beyond said slot for slidably supporting said gate, and means for locking said gate in the closed position including a locking cam pivotally mounted on said gate and projecting laterally beyond said runways, said gate and locking cam having mutually interfitting parts throughout the coextensive portions thereof, and stops extending upwardly from said runways at the outer sides thereof and adapted to be engaged by said cam to lock said gate.

7. In an outlet assembly for the discharge opening of a load containing hopper, in combination, a four sided frame having an opening registering with said discharge opening and a sliding gate for closing said opening, one end of said frame being slotted for the passage of said gate therethrough and the portion above the slot formed by an inverted V-shaped ridge providing a downwardly outwardly sloping wall, runways at the sides of said frame and projecting beyond said slot for slidably supporting said gate, and means for locking said gate in the closed position including a locking cam pivotally mounted on said gate and projecting laterally beyond said runways, and stops extending upwardly from said runways at the outer sides thereof and adapted to be engaged by said cam to lock said gate, said locking cam and gate providing arcuate shaped cam surfaces concentrically formed on a common radius and adapted to be juxtaposed with the lower edge of said downwardly outwardly sloping wall of said ridge along its entire length when said gate is closed to close off the space therebelow.

GEORGE B. DOREY.
